CLAIM

The ornamental design for a pouch, as shown and described.

DESCRIPTION

FIG. 1 is a perspective view of a first embodiment of a pouch showing our new design, the pouch being lined for an orange color;

FIG. 2 is a further perspective view thereof;

FIG. 3 is a plan view thereof;

FIG. 4 is an opposing plan view thereof;

FIG. 5 is an elevational view thereof;

FIG. 6 is a perspective view of a second embodiment of a pouch showing our new design, the pouch being lined for an orange color;

FIG. 7 is a further perspective view thereof;

FIG. 8 is a plan view thereof;

FIG. 9 is an opposing plan view thereof;

FIG. 10 is an elevational view thereof;

FIG. 11 is a perspective view of a third embodiment of a pouch showing our new design, the pouch being lined for a green color;

FIG. 12 is a further perspective view thereof;

FIG. 13 is a plan view thereof;

FIG. 14 is an opposing plan view thereof;

FIG. 15 is an elevational view thereof;

FIG. 16 is a perspective view of a fourth embodiment of a pouch showing our new design, the pouch being lined for a green color;

FIG. 17 is a further perspective view thereof;

FIG. 18 is a plan view thereof;

FIG. 19 is an opposing plan view thereof;

FIG. 20 is an elevational view thereof;

FIG. 21 is a perspective view of a fifth embodiment of a pouch showing our new design, the pouch being lined for a brown color;

FIG. 22 is a further perspective view thereof;

FIG. 23 is a plan view thereof;

FIG. 24 is an opposing plan view thereof;

FIG. 25 is an elevational view thereof;

FIG. 26 is a perspective view of a sixth embodiment of a pouch showing our new design, the pouch being lined for a brown color;

FIG. 27 is a further perspective view thereof;

(Continued)

FIG. 28 is a plan view thereof;

FIG. 29 is an opposing plan view thereof; and,

FIG. 30 is an elevational view thereof.

The broken lines shown in the drawings depict portions of the pouch that form no part of the claimed design.
